JAMES J. O'SHEA, OF DALLAS, TEXAS

SHIRT SETTING DEVICE

Application filed August 18, 1930. Serial No. 476,109.

This invention relates to improvements in laundry apparatus, and particularly to an attachment for use in connection with ironing surfaces on which shirts, with collars attached are to be ironed.

Numerous shirt factories and laundries are now setting shirts, with collars attached, with the collar pressed flat, and the object of the present invention is to provide a shirt setting device that will facilitate the positioning of the shirt and collar on the ironing surface and which will firmly retain the shirt and collar in the desired position on said surface.

Specifically, the invention contemplates an attachment comprising a standard that may be fixed at one end of the ironing surface. Adjustably mounted for vertical movement in said standard, are two elements. One of said elements constitutes an alining or abutment member by means of which the intermediate portion of the edge of the collar may be readily set straight across the ironing surface while the other of said elements is adapted to hold the shirt in place after the edge of the collar has been properly positioned with respect to the alining member.

With these and other objects in view, the invention consists of certain details of construction and combinations and arrangements of parts all as will hereinafter be more fully described, and the novel features thereof particularly pointed out in the appended claims.

In the accompanying drawings:

Fig. 1 is a view, in front elevation, of a preferred embodiment of my invention, certain parts being broken away for the purpose of better illustration.

Fig. 2 is a vertical sectional view on the line 2—2 of Fig. 1.

Fig. 3 is a side elevational view.

Fig. 4 is a horizontal sectional view on the line 4—4 of Fig. 3.

Fig. 5 is an elevational view of a portion of the rear face of the device.

The present device comprises a standard 10 which may be of any desired type, but preferably it is U-shaped in cross section, as shown in Fig. 4, with a slot or guideway 11 extending vertically therein. The standard

is also formed with a base portion 12, which is adapted to be affixed to the ironing surface as by the screws 13.

As illustrated in Figures 3 and 4, a shirt 14, with collar 15, attached, is adapted to be placed on the ironing surface 16 and for the purpose of facilitating the setting or the rear portion of the collar of a collar attached shirt square with the shirt proper, there is an alining element or attachment in the form of an abutment provided on the standard 10. This attachment consists of a plate 17, having two of its opposite edges offset as at 18 and 19. The offset edge portion 18 is turned upwardly and has an opening therein through which a threaded bolt 20 projects, said bolt also projecting through the guideway 11 in the standard, so that its protruding end may receive a nut 21. As will be readily understood, this attachment can be clamped in any desired position vertically of the standard by tightening up the nut 21. The other edge 19 of the plate, is turned downwardly, and when a shirt is to be placed on the ironing surface, this attachment 17 is lowered, so that the bottom edge of the down-turned portion 19 is substantially in contact with the ironing surface whereby the collar 15 may easily be positioned on the ironing surface with the intermediate portion of its edge positioned against the outer surface of said down-turned portion 19. It might be mentioned that the ironing surface is preferably formed by a pad suitably attached to a table or other support 22. The vertical adjustability of the alining member 17 permits the facile replacement of the pad or other ironing surface 16 and also makes possible the close contact of the flange 19 with pads of different thicknesses as well as compensation for reduction in thickness due to long use.

Also carried on the standard is a second attachment for firmly holding the shirt in place after the shirt collar has been positioned against the alining element. This shirt-holding attachment consists of a U-shaped member having two depending legs 23, 24, projecting downward from an intermediate portion 25. Adjacent their lower ends, legs 23,

24, are braced by a spacer 26, and projecting through the leg 24 and through the guideway 11 are two threaded bolts 27 on the ends of which there are rectangular washers 28, 5 these washers being locked in the guideway whereby the holding attachment may be moved vertically in the way. To releasably retain this holding member in any desired position there is a comparatively long bolt 10 29, which extends through the standard 10 and both of the legs 23, 24, the end of said bolt projecting beyond the front face of leg 23, so as to receive a nut 30, by which the holding member can be clamped securely 15 on the standard. In order to retain the holding member at a point well above the ironing surface, as for instance, when the shirt is being placed on or removed from the ironing surface, the intermediate portion 25 of said 20 holding member has thereon a housing 31, in which there is slidably secured a latch or bolt 32, provided with a finger piece 33 projecting through a slot 34 in said housing. Bolt or latch 32 is yieldingly urged outwardly from the housing by a spring 35, so that when the holding attachment is raised to the point in which it is illustrated in Figures 1 and 2, the latch or bolt 32 will be projected over the upper end of standard 10 so 25 as to retain the holding attachment in its elevated position. When it is desired to lower the holding attachment, the bolt or latch 32 is retracted by means of the finger piece 33 to a point where it will clear the 30 standard.

As shown in Figures 3 and 4, after the shirt has been properly positioned on the ironing surface with respect to the abutment member 19, the holding attachment is lowered and clamped to the standard in a position to engage the inner surface of the rear portion of the collar and firmly retain the shirt on the ironing surface with the edge of the collar against the abutment member 40 while the shirt is being pressed. It will also be noted that the front surface of the standard 10 is recessed as at 36 to receive the upturned portion 18 of the alining attachment, thus holding said attachment against wabbling, so to speak, on the standard.

What I claim is:

1. In a setting device for shirts having attached collars, the combination of a standard 55 an abutment member carried by said standard against which the rear portion of the collar edge is alined, and means on said standard for holding the shirt on an ironing surface, with the shirt collar in engagement 60 with said abutment member.

2. In a shirt setting device for shirts having attached collars, the combination of a standard, a collar abutment member on said standard, and means vertically slidable on 65 said standard and engageable with the shirt

collar to maintain the edge of the collar against said abutment member.

3. In a setting device for shirts having attached collars, the combination of a standard 70 adapted to be mounted on an ironing surface, a collar abutment member, a positioning member on said standard engageable with the inner surface of a shirt collar on said ironing surface when the rear portion of the edge of the collar is against said abutment member, and fastening means engaging said positioning member and standard so that the shirt and collar are firmly held on said ironing surface.

4. In a shirt setting device for shirts having collars attached thereto, the combination 80 of a standard having a vertical way therein, a collar abutment member slidable in said way and means slidable in said way and projecting laterally from said standard beyond said abutment member and adapted to clamp a shirt on an ironing surface with the edge of the collar against said abutment member.

5. In a shirt setting device for shirts having attached collars, a standard having a vertical way therein, an abutment member vertically adjustable in said way, means for locking said abutment member in adjusted position, shirt clamping means slidable in said 90 way and means for locking said clamping means in adjusted position.

6. A device for setting the collar of a collar attached shirt flat with respect to the shirt proper, comprising a vertical standard 100 adapted for mounting upon a shirt pressing surface, an abutment member against which the rear portion of the collar edge is disposed, and a vertically movable member guided by said standard and having a foot portion which engages the inner surface of the rear portion of the collar to hold said portion flat upon the shirt pressing surface.

7. A device for setting the collar of a collar attached shirt flat with respect to the shirt proper, comprising a vertical standard 110 adapted for mounting upon a shirt pressing surface, a straight edged abutment member against which the rear portion of the collar edge may be alined, and a vertically movable member guided by said standard and having a foot portion which engages the inner surface of the rear portion of the collar to hold said portion flat upon the shirt pressing surface.
